UNITED STATES PATENT OFFICE.

FRITZ MINK, OF PHILADELPHIA, PENNSYLVANIA, ASSIGNOR TO THE KEY-STONE WATCH CASE COMPANY, OF PENNSYLVANIA.

WATCH-BOW FASTENER.

SPECIFICATION forming part of Letters Patent No. 439,414, dated October 28, 1890.

Application filed April 15, 1890. Serial No. 347,987. (No model.)

To all whom it may concern:

Be it known that I, FRITZ MINK, of the city and county of Philadelphia, and State of Pennsylvania, have invented an Improvement in 5 Watch-Bow Fasteners, of which the following is a specification.

My invention has reference to watch-bow fasteners; and it consists of certain improvements which are fully set forth in the following specification and shown in the accompanying drawings, which form a part thereof.

The object of my invention is to produce a convenient and economical device for fastening the ends of the bow to the pendant of a 15 watch-case.

In carrying out my invention I provide the pendant on diametrically-opposite sides with apertures through which are inserted internally-screw-threaded socket-pieces adapted to be screwed upon the ends of the bow. These 20 socket-pieces are provided upon their inner ends with flanges or projections to prevent them being withdrawn through the apertures of the pendant and are locked therein by 25 means of an interior locking-piece.

The details of my invention are more fully set forth in the description of the drawings, which follows:

Figure 1 is a sectional side elevation of a 30 watch-case pendant and bow illustrating my invention. Fig. 2 is a cross-sectional view of the same on the line $x-x$ of Fig. 1. Fig. 3 is a similar view to Fig. 1, illustrating a modification of my invention; and Fig. 4 is a cross- 35 sectional view on the line $y-y$ of Fig. 3.

A is the watch-case pendant.

B is the bow, having screw-threaded ends b. The watch-case pendant A is provided with apertures a upon diametrically-opposite sides.

40 C are internally-screw-threaded socket-pieces inserted from the interior of the pendant through the apertures a, and provided on their inner ends with flanged rims or projections c to prevent their being withdrawn 45 through the apertures a.

D is the interior locking-piece to lock the socket C in place.

In Figs. 3 and 4 the inner face of the pend-

ant about the apertures a is recessed or countersunk to receive the rims or flanged ends c 50 of the socket-pieces, and the locking-piece D is made smooth upon its outer surface, while in Figs. 1 and 2 these flanged ends c are shown projecting within the interior of the pendant, and the locking-piece D is made with its lower 55 part of smaller diameter, so as to fit against the flanged ends, while the upper portion bears against the inner surface of the pendant. It will be seen that in a construction of this kind screw-threads upon the ends of the bow b may 60 run in the same direction, the tubular socket-pieces C being screwed upon them from the interior of the pendant.

While I prefer the details of construction 65 which are here shown, I do not limit my invention to them, as it is apparent that they may be modified in many ways without departing from the spirit of my invention.

What I claim as new, and desire to secure by 70 Letters Patent, is—

1. The combination, with a watch-bow having its ends screw-threaded, of a pendant provided on diametrically-opposite sides with apertures, and internally - screw - threaded socket-pieces adapted to be inserted from the 75 interior of the pendant through said apertures and screwed upon the ends of the bow.

2. The combination, with a watch-bow having its ends screw-threaded, of a pendant provided on diametrically-opposite sides with 80 apertures, internally-screw-threaded sockets adapted to be inserted from the interior of the pendant through said apertures and screwed upon the ends of the bow, and flanges or projections upon the ends of said socket-pieces to prevent them being withdrawn 85 through said apertures.

3. The combination, with a watch-bow having its ends screw-threaded, of a pendant provided on, diametrically-opposite sides with 90 apertures, internally-screw-threaded, sockets adapted to be inserted from the interior of the pendant through said apertures and screw-threaded upon the ends of the bow, flanges or projections upon the ends of said socket-pieces 95 to prevent them being withdrawn through

said apertures, and an internal locking-piece within the pendant to lock the ends of the sockets in place.

4. In a watch-bow fastener, the combination of a watch-bow having its ends screw-threaded, a watch-case pendant, and internally-screw-threaded socket-pieces to receive the screw-threaded ends of the bow separate from the

pendant but adapted to be fitted thereto to fasten the ends of the bow to it.

In testimony of which invention I have hereunto set my hand.

FRITZ MINK.
